H. P. ARNT

DEVICE FOR AND METHOD OF ASSEMBLING COMPOSITE METAL WHEELS

Filed July 16, 1921

FIG. 1.

FIG. 2.

INVENTOR:
HERALD P. ARNT

BY HIS ATT'Y

Law B. Mueller.

UNITED STATES PATENT OFFICE.

HERALD P. ARNT, OF LAKewood, OHIO.

DEVICE FOR AND METHOD OF ASSEMBLING COMPOSITE METAL WHEELS.

Application filed July 16, 1921. Serial No. 485,327.

To all whom it may concern:

Be it known that I, HERALD P. ARNT, a citizen of the United States, residing at 1552 Robinwood Ave., Lakewood, in the 5 county of Cuyahoga and State of Ohio, have invented a new and useful improvement in Devices for and Methods of Assembling Composite Metal Wheels, of which the following is a specification, the principle of the invention being herein explained and the best mode in which I have contemplated applying that principle, so as to distinguish it from other inventions.

My invention pertains to a device for assembling a composite metal wheel and more particularly to a device for positioning the spokes.

All-metal wheels provided with tubular spokes are rapidly coming into vogue owing to the growing scarcity and therefore increased cost of the wood best adapted to their manufacture. It is common practice to employ a felloe provided with as many equispaced holes each for the reception of 25 a spoke end together with a suitable hub structure for binding together the nave ends of the spokes. These spokes are readily put in place by hand with the exception of the last one owing to the fact that the 30 others are not pressed tightly enough against each other to leave sufficient space for the nave end of the last spoke. Accordingly, my invention is especially adapted to facilitate insertion into place of the 35 last spoke.

Adverting to the drawings:

Figure I is mainly a plan view having one portion shown in section, of a nearly assembled all-metal wheel showing my device as to be used in conjunction.

Figure II is a section on line II-II of Figure I.

A felloe 1 is fashioned with twelve equispaced holes 2. Tubular spokes 3 have 45 reduced outer ends 4 for insertion through the openings 2 preparatory to being punched or spun over. The nave ends 5 of the spokes are enlarged to resemble the conventional design of a wooden spoke and are 50 fashioned with two pairs of oppositely disposed flat sides. One pair of sides 6 are intended to lie in radial planes and to firm-

ly abut corresponding sides of adjacent spokes. The other pair of sides 7 are all to lie in parallel circular planes of the 55 wheel.

All the spokes except one are readily put in place by hand to give the partly assembled wheel the appearance furnished in Figure I. Thereafter I propose to lay 60 the assembled parts upon a block 8 provided with a cut-out or depression 9 so that the space intended to be occupied by the last spoke is directly over the depression 9. As will be readily understood, the nave ends 65 of the spokes should have a tight abutting relationship which, however, they will not assume until forced into such positions. After the first eleven spokes have been inserted through the holes in the felloe there 70 will be enough looseness therebetween to make difficult the manual insertion of the inner end of the last spoke. It therefore becomes necessary temporarily to hold the eleven spokes pressed against each other 75 and the two bordering the unoccupied space in such a position as to enable the nave end 5 of the last spoke to be readily slipped into place following insertion of its end 4 through its appropriate opening 2 in the 80 felloe. For this purpose, I have provided a wedge member 10 substantially conforming in shape, that is, bounded by two converging size corresponding in spaced relation to that of the flat sides 6. Optionally 85 having a screw threaded connection at 11 with the wedge 10 is a rod 12 to be passed through that spoke 3 which is in diametrical alinement. The outer end of the rod 12 projects beyond the felloe 1 and is there 90 fashioned with screw threads 13 with which a threaded nut 14 carrying handles 15 co- 95 operates.

In operation, after the first eleven spokes have been arranged in place with their outer 95 ends 4 projecting through the holes and their nave ends 5 resting upon the block 8, and while the nut 14 is detached from the screw threads 13, the rod 12 is passed through that spoke which is opposite the 100 vacant space after which the nut 14 is applied and when screwed up acts to draw the wedge member 10 into the position it is shown to occupy in Figure I thereby

causing the nave ends 5 of the eleven spokes to be tightly pressed against each other. While in such position the outer end of the last spoke is inserted through the opening 5 2 in the felloe for its accommodation whereas the nave end 5 of such last spoke will rest upon the wedge member 10. A few downward taps of a hammer will then cause the end 5 of the last spoke to partially 10 force out the wedge member 10 as appears in Figure II the nave end 5 being then in a position to substitute for the function of the wedge member 10. Then the nut 14 may be removed, and the wedge member 10 completely 15 forced out and the rod 12 withdrawn. Finally the wheel is turned sufficiently to bring the partially inserted spoke over the raised portion of the block 8 when it may be quickly driven to a proper 20 position.

I claim:—

1. The combination, for use in assembling in a felloe a plurality of wheel spokes having wedge-shaped nave ends, of a wedge-shaped member adapted to fit between a pair of spoke navies which are on each side of a single missing spoke space and further adapted to press the nave ends of the felloe connected spokes circumferentially against 25 each other and means connected with said felloe and with said member for actuating the latter to its functioning position.

2. The combination intended for use with a felloe fashioned with an opening in its 30 periphery and an open tubular spoke having one end projected through said felloe opening; comprising a rod passed through said spoke, a wedge on one end of said rod, and means for adjusting said rod and hence said 35 wedge relative to said felloe.

3. The combination intended for use with a felloe fashioned with an opening in its periphery and an open tubular spoke having one end projected through said felloe opening; comprising a rod passed through said 40 spoke and having a screw threaded end projecting beyond the felloe-inserted end of said spoke, a wedge detachably carried on the other end of said rod and a nut for 45 drawing said wedge toward said felloe.

4. The combination intended for use in assembling hollow spokes and a felloe having circumferentially arranged openings in all except one of which openings the outer 50 end of a spoke is inserted, comprising a block provided at one place with a cut-out and adapted to support the partially assembled wheel with the axis of its missing spoke over said cut-out, together with a rod 55 passed through the spoke which is diametrically opposite said cut-out, a wedge carried by said rod over said cut-out and adapted to spread apart the nave ends of laterally adjacent spokes and a nut cooperating with 60 the other end of said rod to draw said wedge 65

into position to press the nave ends of all of said spokes against each other preparatory to inserting the outer end of the last spoke into its felloe hole and causing its nave end to force said wedge down into the cut-out. 70

5. A device of use in assembling a tubular spoke wheel comprising a member adapted to be passed through a spoke and a hole in a felloe, said member having an inner end beyond the center of the felloe with reference to the felloe hole through which it is inserted, a wedge connected with one end of said member and an adjusting nut in screw-threaded connection with the other end adjacent the outer side of the felloe. 80

6. The combination intended for cooperation with a felloe provided with openings in which openings the outer ends of all except one of a plurality of hollow spokes are projected, comprising a rod passed through one of said openings and through the spoke which occupies said particular opening, said rod extending to a point beyond the center of said felloe, a wedge carried by said part within the bounds of said felloe and at a point which the nave end of the missing spoke will occupy, and a device cooperating with said part outside of said felloe and adapted to draw said wedge toward the latter to press the nave ends of the spokes against each other preparatory to the fitting of the last spoke into place. 85

7. The combination intended for assembling use with hollow spokes and with a wheel felloe provided with circumferentially arranged openings, all except one of which are occupied by spoke ends, said combination comprising a rod passed through one of said felloe openings and one of said spokes and extending to a point beyond the center of said felloe, a wedge carried by the end of said rod, and a device cooperating with said rod and with the outer side of said felloe and adapted to draw said wedge tightly between the centrally positioned 90 ends of two spokes inserted in the felloe openings whereby to permit of the insertion of the last complementary spoke with its nave end substituted for said wedge. 95

8. The method of assembling wheel spokes with a felloe provided with circumferentially arranged holes, which consists in inserting the outer ends of all but one of said spokes into different ones of said holes, forcing a wedge between the two spokes which are adjacent the space provided for the missing spoke, inserting the outer end of the remaining spoke in its felloe hole and then causing the nave end of said last mentioned spoke to be substituted for said 100 wedge. 105

9. The method of assembling wheel spokes having wedge-shaped nave ends with a felloe provided with circumferentially arranged holes, which consists in inserting the outer 110

ends of all but one of said spokes into different ones of said holes, drawing a wedge corresponding in size and shape to the spoke navels between the two spokes which border 5 the space provided for the missing spoke, supporting the nave ends of the inserted spokes on a block provided with a cut-out

below said fitted wedge, inserting the outer end of the remaining spoke in its felloe hole and then driving the nave end of said last mentioned spoke down to force out to wedge into said cut-out space of the block. 10

Signed by me this 21st day of June, 1921.
HERALD P. ARNT.
